TIRE FOR A VEHICLE WHEEL

Roger Derek Sanders, Barton-under-Needwood, England,
assignor to Dunlop Limited, London, England

Filed Aug. 2, 1974, Ser. No. 494,296

Claims priority, application Great Britain Feb. 6, 1974

Term of patent 14 years

Int. Cl. D12—15

U.S. Cl. D12—142

The figure is a perspective view of a tire for a vehicle wheel showing my new design; it being understood that the tread pattern is repeated throughout the circumference of the tire as shown schematically by solid lines, and the opposite side is the same as that shown.

I claim:

The ornamental design for a tire for a vehicle wheel, as shown and described.
